UNITED STATES PATENT OFFICE.

A. DOUGLAS AND S. S. SHERWOOD, OF NEW YORK, N. Y.

SLIDE AND FASTENING FOR SKIRT-HOOPS.

Specification of Letters Patent No. 22,355, dated December 21, 1858.

To all whom it may concern:

Be it known that we, ALEXANDER DOUGLAS and SAMUEL S. SHERWOOD, of New York, in the county of New York and State of New York, have invented a new and Improved Fastening and Slide for Skirt-Hoops, the construction and operation of which we have described in the following specification and illustrated in its accompanying drawings with sufficient clearness to enable competent and skilful workmen in the arts to which it pertains or is most nearly allied to make and use our invention.

Our said invention consists in making the slide and the fastening to the hoop of a single piece of sheet metal, by making transverse incisions through the metal along the middle of it, springing out those divisions in opposite directions, inserting the end of the hoop, swaging the divisions down upon it, upon opposite sides, as shown, the divisions or bars thus formed by making said incisions still retaining their connection at both their ends to the extremities of the plate as represented in the drawings, and finally, closing the sides of the plate loosely over that part of the hoop which is intended to slide through it, thus forming a clamp for the end of the hoop, to slide through for the purposes of expansion and contraction, as hereinafter more fully set forth.

In the accompanying drawings, Figure 1 is a plan of our improved fastening and slide as attached to a hoop for dress skirts. Fig. 2 is a side elevation of it. Fig. 3 is an end elevation, showing the fastening formed upon the end of the hoop, and the slide as yet unclosed. Fig. 4 is an end view of the fastening and slide completely formed. Fig. 5 is an edge view of the piece of metal of which the slide and fastening is made, partially formed, prepared to be put upon the end of the hoop. Fig. 6 is a side elevation of the same thing in the same condition. Fig. 7 is also a side elevation, reverse to Fig. 6.

A. is the hoop, which is or may be a flat steel spring, covered with web or cloth or braid. It is necessary to secure the covering at the ends, and it is at the same time desirable to provide some means for the expansion and contraction of the hoop to suit the pleasure of the wearer. To accomplish both these objects at once, we cut out small nearly square pieces of sheet metal, and by means of punches made for the purpose, cut

and swage them into the form shown in Figs. 5, 6 and 7, the divisions *b*, being forced out in one direction, and the divisions *c*, in the other direction, in such a manner as to allow the end of the hoop to be inserted between, and after this has been done, the divisions *c*, are stamped down as tightly as may be upon the braid or web which surrounds the hoop, and the fastening for the end is thus formed—the divisions *b*, being upon one side of the hoop and the divisions *c*, upon the other. At the same time the lips *d*, are brought up as shown in Fig. 3, to form the slide. That part of the hoop which is to slide through it is then inserted, together with a thin piece of steel to prevent the slide being formed too closely upon the hoop; the lips *d*, are then closed over, as shown in Figs. 1 and 4, and the slide is formed of the extremities of the plate from the middle of which the fastening is formed of the bars *b* and *c*. The steel which has been put in to prevent its being too closely formed, may then be withdrawn, and the fastening and slide are ready for use. It should be observed that there should be a fastening and slide upon each end of the hoop, and as one of these ends passes outside and the other inside of the body of the hoop, the slide should accordingly be located upon opposite sides as shown to correspond with their relative positions to the hoop. The fastening thus formed from the bars *b* and *c*, which are connected at both their ends to the extremities of the plate from which the lips which make the slide are formed is much stronger, and more firm in its attachments to the hoop than it would be if made by folding over lips of metal upon the end of the hoop, leaving their extremities disconnected, as in the latter case, there is nothing but the elasticity of the metal to retain the fastening upon the end of the hoop, while in the construction we have described and shown with the bars *b* and *c*, connected at both the ends to the extremities of the plate from which they are formed, nearly the whole tensile strength of the metal is made available in holding the fastening upon the hoop.

We are aware that a slide and fastening for skirt hoops has been made of a single piece of metal, so as to embrace and fasten to the end of the hoop, while a part of the hoop near the other end was permitted to slide through it, or in other words, through

a loop which formed a part of it, the attachment to the hoop being formed of loops folding in one direction from a central piece upon the end of the hoop and the slide or 5 loop for the hoop to slide in being formed of loops folding from said central piece in the opposite direction, as seen in the patent granted to R. J. Mann, June 22d, 1858, and not in either case forming a continuous connection and junction of metal around the hoop. We are also aware that the tapes of skeleton skirts have been attached to the hoops by a clamp made by folding lips over 10 from the ends, and punching up a longitudinal strip of the metal to hold the tapes, as shown in the patent granted to A. Smart, August 31st, 1858. We make no claim to either of these devices.

The particular improvement which constitutes our said invention, and which we claim as having been originally and first invented by us, is— The combined clamp and slide, made entire of one piece, by forming the clamp of the divisions *b* and *c*, and the slide of the 15 lips *d*, as described; the divisions *b* and *c*, being entire, and connected at both ends to the plate as shown, thus forming a continuous connection around the end of the hoop, for the purpose stated.

ALEX. DOUGLAS.
SAML. S. SHERWOOD.
